ASH TRAY.

Albert A. Vuccino, New York, N. Y.

Application March 18, 1935, Serial No. 11,700

REISSUED

6 Claims. (Cl. 131—51)

This invention relates to a combination ash tray and cigar and cigarette extinguishing device.

The main object of the invention is to provide an ash tray for holding the burnt out ashes of 5 cigars and cigarettes and having liquid means for extinguishing the lighted ends thereof.

Another object of the invention is to provide the device with a water reservoir for supplying water to the extinguishing means.

Another object of the invention is to regulate 10 the amount of water supplied to the extinguishing means.

A still further object of the invention is to provide a swinging trough partly submerged in 15 a reservoir of water for carrying the water from the reservoir to the extinguishing means and then back again to the reservoir.

Other objects will appear as the disclosure progresses. The drawing is merely intended to indicate a possible embodiment of the invention. 20 It is obvious that the actual needs of manufacture may necessitate certain mechanical changes. It is therefore not intended to limit the invention to the embodiment illustrated but 25 rather to define such limits in the appended claims.

Figure 1 is a top view of the device with the cover partly broken away.

Figure 2 is a section on line 2—2 of Figure 1. 30 Figure 3 is a side view of the device.

Figure 4 is a section on line 4—4 of Figure 3.

Referring now to the drawing in detail it will be seen that the device comprises a body 1 divided into a reservoir 2 for holding a supply 35 of water and a compartment 3 for holding an ash tray 4. The reservoir is divided into three longitudinal compartments 5, 6 and 7 by the walls 8 and 9. Above the reservoir is a cover 10.

Mounted in the longitudinal center of the device 40 on bearings 11 attached to the wall 12 is a swinging water trough 13. A pin 14 passes through ears 15 in the trough and fits in said bearings. The bearings are open at the top so the trough can be removed when necessary. At 45 both ends of the trough are cups 16 and 17. The cup 16 is normally submerged in the water 18 contained in the reservoir. The portion of the trough housed in the reservoir is longer and overbalances the protruding portion.

50 The operation of the device is as follows: The reservoir 2 is filled with water 18, the openings 19 in the walls 8 and 9 allowing the water to flow from one compartment to the other compartments and the swinging trough mounted on 55 its bearings. Now when it is desired to ex-

tinguish a cigarette, the cigarette with its lightened end is placed in the cup 17 and pressed down so the trough will swing down as shown in dotted lines in Figure 2. As the submerged cup 16 is lifted up the small amount of water contained in said cup and in part of the submerged trough 5 will flow down to the cup 17 and extinguish the lightened end of the cigarette. When the weight on the cup 17 is released the trough will fall back to its natural position as shown in full 10 lines in Figure 2. The capacity of the cup 17 is greater than the capacity of the submerged end of the trough so there will be no overflow when the cup 17 is swung downwardly. Numeral 20 designates a set of grooved cups for holding 15 the cigars or cigarettes.

It will thus be seen that I have provided a novel, efficient and simple constructed device for extinguishing the lighted ends of cigarettes and cigars and for holding their ashes. The oscillating trough is removably held in place so it can be easily removed. The tray 4 can also be removed to clean out the ashes.

Having described my invention, I claim:

1. In a device of the class described, a body 25 member, a reservoir for holding a supply of water, and an oscillating trough associated with said body member, one end of said trough normally submerged in said reservoir, the other end raised above the water line, whereby when said 30 second mentioned end is depressed water is caused to flow to said second mentioned end.

2. In a device of the class described, a body member, a reservoir for holding a supply of water, an oscillating trough associated with said 35 body member, and cups at the ends of said trough, one end of said trough normally submerged in said reservoir, the other end raised above the water line, whereby when said second mentioned end is depressed water is caused to 40 flow to said second mentioned end.

3. In a device of the class described, a body member, a reservoir for holding a supply of water in said body member, an outward extending compartment, an ash tray resting in said outward extending compartment, an oscillating trough associated with said body member, and cups at the 45 ends of said trough, one end of said trough normally submerged in said reservoir, the other end raised above the water line, whereby when said second mentioned end is depressed water is caused to flow to said second mentioned end.

4. In a device of the class described, a body member, a reservoir for holding a supply of 50

water, and an oscillating trough removably mounted on a wall of said body member, one end of said trough normally submerged in said reservoir, the other end raised above the water line, 5 whereby when said second mentioned end is depressed water is caused to flow to said second mentioned end.

5. In a device of the class described, a body member, a reservoir for holding a supply of 10 water, an oscillating trough removably mounted in bearings attached to a wall of said body member, and cups at the ends of said trough, one end of said trough normally submerged in said reservoir, the other end raised above the water line, 15 whereby when said second mentioned end is de-

pressed water is caused to flow to said second mentioned end.

6. In a device of the class described, a body member, a reservoir for holding a supply of water in said body member, an outward extending compartment, an ash tray resting in said outward extending compartment, an oscillating trough removably mounted in bearings attached to a wall of said body member, and cups at the ends of said trough, one end of said trough normally submerged in said reservoir, the other end raised above the water line, whereby when said second mentioned end is depressed water is caused to flow to said second mentioned end.
